(74) *Attorney, Agent, or Firm* — Barry Choobin; Patent 360

(57) **CLAIM**

The ornamental design for a liquid dispenser with air freshener kit, as shown and described.

DESCRIPTION

FIG. 1 is an exploded perspective view of a liquid dispenser with air freshener kit, showing my new design;

FIG. 2 is another exploded perspective view thereof;

FIG. 3 is an exploded front view thereof;

FIG. 4 is an exploded rear view thereof;

FIG. 5 is an exploded right side view thereof;

FIG. 6 is an exploded left side view thereof;

FIG. 7 is an exploded top view thereof;

FIG. 8 is an exploded bottom view thereof; and,

FIG. 9 is a perspective view of the liquid dispenser with air freshener kit.

The broken lines shown in the figures illustrate the air freshener kit and portions of the liquid dispenser that forms no part of the claimed design.

1 Claim, 9 Drawing Sheets
